UNITED STATES PATENT OFFICE.

IRVIN C. SOUDERS, OF DAYTON, OHIO.

DESIGN FOR A BOTTLE.

SPECIFICATION forming part of Design No. 31,622, dated October 10, 1899.

Application filed September 11, 1899. Serial No. 730,179. Term of patent 14 years.

To all whom it may concern:

Be it known that I, IRVIN C. SOUDERS, a citizen of the United States, residing at Dayton, in the county of Montgomery and State of Ohio, have invented a certain new and useful Design for a Bottle; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figures 1 and 2 are views of opposite sides of my design. Fig. 3 is a cross-sectional view on the line xx of Fig. 1.

As is shown in the drawings, the leading or material feature of my design consists of a series of sunken rectangular panels A B C D on one side of the bottle. These panels are separated by transverse bars $a b c$. The top panel D is of a gable or half-diamond shape. A bird E of the crane or stork species occupies a position to one side of the centers of the two central panels B C. The division-bars $b c$ are broken to allow the figure of the

bird to extend through the two central panels B C with its bill or beak projected into the uppermost panel D. The opposite side of the bottle, as shown in Fig. 2, has a single ob- 30 long rectangular sunken panel G, capped by a sunken panel H of a gable or half-diamond shape. The panels G and H are separated by a transverse bar I. The neck of the bottle joins the widest part thereof by tapering sides 35 J J. The edges or smaller sides K K are flat throughout the length of the body of the bottle, as shown in Fig. 3.

The several figures and ornamentations are produced in the material forming the bottle 40 in a manner well known to the art of glass-blowing.

Having described my invention, I claim as new and desire to secure by Letters Patent—

The design for a bottle as herein shown and 45 described.

In testimony whereof I affix my signature in presence of two witnesses.

IRVIN C. SOUDERS.
